FLASH HOLDER

David E. Hansen, Rochester, N.Y., assignor to Eastman Kodak Company, Rochester, N.Y., a corporation of New Jersey

Filed Jan. 10, 1963, Ser. No. 73,122

Term of patent 14 years

(Cl. D61—1)

FIG. 2

FIG. 4

FIG. 5

FIG. 1

FIG. 6

FIG. 3

FIG. 1 is a front elevational view of a flash holder showing my new design;

FIG. 2 is a rear elevational view thereof;

FIGS. 3 and 4 are side elevational views of opposite sides thereof;

FIG. 5 is a top plan view thereof; and

FIG. 6 is a bottom plan view thereof.

The broken line showing of a flash lamp in FIG. 1 is for illustrative purposes only.

I claim:

The ornamental design for a flash holder, as shown and described.
